UNITED STATES PATENT OFFICE.

NELSON S. WELK, OF ATHENS, OHIO, ASSIGNOR TO THE McBEE BINDER CO., OF ATHENS, OHIO, A CORPORATION OF OHIO.

FILING TRAY.

Application filed February 25, 1926. Serial No. 90,477.

This invention relates to an improvement in filing trays for cards, etc., and has particular reference to a follower for such tray.

An object of the invention is the provision of a follower of improved construction, for use in conjunction with mechanism disclosed in my copending application, Serial Number 90,475, filed Feb. 25, 1926.

An important object of the invention resides in the details of construction whereby the follower may be adjusted longitudinally of the tray, and upon release, will automatically lock itself against accidental movement.

A further object of the invention resides in the extremely simple construction of carriage for the follower, and the associated locking mechanism.

Other important objects and advantages of the invention will be apparent during the course of the following description, reference being had to the accompanying drawings, wherein like reference characters are employed to designate like parts throughout.

Referring to the drawings:

Fig. 1 is a perspective view of a filing tray embodying the invention.

Fig. 2 is a vertical, longitudinal section therethrough,

Fig. 3 is a transverse, vertical section therethrough,

Fig. 4 is a perspective view of the follower and associated carriage, removed from the tray, and

Fig. 5 is a slightly enlarged central, vertical section through the follower carriage in the tray.

Referring specifically to the drawings, the numeral 10 designates the front wall of the tray, 11 the side wall and 12 the rear wall. The walls, 10, 11 and 12, are formed from a single sheet of suitably stiff sheet metal, bent upon itself at its upper edges, as indicated at 13, to provide a reinforced and smooth contacting surface. The walls are further reinforced by a substantially rigid band 14, extending therearound, adjacent the upper edges, and projecting slightly beyond the front and end walls 10 and 12. A bottom 15 is suitably attached to the side and end walls 10 and 12, as by spot welding, or, as shown, they may be formed of one piece. The opposite side of the tray is formed open

and is normally closed by a swinging door, designated as a whole by the numeral 16. 55 The door and associated parts are identical with that disclosed in the above-mentioned application and will require no detail description herein. The ends 10 and 12, adjacent such opening, are further reinforced 60 by vertical corner posts 17, welded or otherwise attached thereto. The front end 10 is provided with a handle 18 and an open card-pocket 19.

The door 16 is adapted for vertical swinging movement and when in the outermost position, lies in a substantially horizontal plane. The purpose of the door 16 is to enable the operator to gain ready access to the cards contained in the tray and, if desired to slide a card or cards outwardly for further reference, such cards being supported upon the surface of the door. 65

It is desirable that means be provided to prevent distortion of the tray due to the 75 door opening, and to overcome this objection, a strip 19 is welded or otherwise attached to the outer surface of the door, in alignment with the band 14, and extending beyond the ends of the door to form in effect 80 a continuation of the band 14. The projecting ends of the strip 19 are provided with openings for the reception of pins 20, carried by the corner posts 17. It will thus be seen that when the door is in the closed position, 85 the pins will engage within the openings, consequently, any stress upon the adjacent portions of the ends of the tray will be supported by the strip 19.

The numeral 21 designates a substantially 90 U-shaped track, extending longitudinally of the tray for its entire length, and bolted or otherwise rigidly attached to the bottom thereof, as shown. This track is provided with inturned flanges 22, to be engaged by 95 the carriage of a follower, to be described. Inverted U-shaped fillers 23 are positioned upon the bottom of the tray upon opposite sides of the track 21, and completely cover the bottom of the tray. The purpose of 100 these fillers is to bring the level of the tray bottom up to the level of the track 21. The fillers may be bolted or otherwise rigidly attached within the tray.

The numeral 24 designates a follower 105 plate, hingedly mounted upon a transverse

bar 25, as shown at 26. The plate 24 is limited in its forward swinging movement by engagement of its lower edge with the forward edge of the bar 25. Rearward movement of the plate is limited by a pair of inclined brackets 27, suitably rigidly attached to the bar 25. The bar 25, together with the plate 24, is adapted to partake of longitudinal sliding movement upon the track 21. The bar 25 has rigidly attached thereto a horizontally U-shaped carriage 28 with opposite edges downwardly offset, which engage beneath the flanges 22, and have sliding contact therewith. As clearly shown, the carriage 28 is offset sufficiently to raise the bar 25 above the working surface of the tray, whereby undue friction will be avoided during the movement of the follower. To avoid tilting of the follower laterally, filler strips 30 have been provided, which are rigidly affixed to the bottom of the bar 25 directly over the flanges 22, and are adapted to slide thereon.

It becomes necessary to provide means for locking the follower plate against accidental movement under pressure of the filed matter, and to accomplish this, a block 31 is arranged adjacent the rear edge of the bar 25, and connected thereto through the medium of a flat leaf spring 32. The spring 32 is bolted to the bar 25 by means of bolts 33, such bolts serving to also attach the carriage 28. The block 31 is grooved at its ends for engaging over the flanges 22, and adapted to slide thereon with the bar 25 and carriage 28. The spring 32 is bowed downwardly and exerts a downward movement to the block 31. It will therefore be obvious that such movement under the action of the spring 32 will clamp the block 31 in frictional engagement with the flanges 22. To release this frictional engagement, it is necessary to raise the block 31 against the tension of the spring sufficient to bring the same into alignment with the carriage 28, at which time the bar and associated elements may be freely moved along the track.

To facilitate the movement of the follower and to release the locking block 31, an arm 34 is bolted to the block 31, as at 35, and is slightly, rearwardly offset from the vertical. The upper end of the arm 34 is bent rearwardly at a greater angle, for engagement by the finger of the operator. As clearly shown in Figs. 1 to 3, the plate 24 is notched out, as at 36, and is further provided with a depression 37, which acts as a seat for the thumb of the operator. When it is desired to release the carriage for movement, the operator engages the plate 24 with the thumb and the arm 34 with the finger, pressing them together, at which time the carriage is released and the follower is free for sliding movement.

65 In order to retain the follower in rigid

vertical position, and to positively hold the carriage in locked position, a hinged plate 38 is carried by the rear wall of the plate 24, and is adapted to be swung upward and into contact with the arm 34. Upward movement of the plate 38 is limited by a stop lug 39, carried by the arm 34. One corner of the plate 38 is bent upwardly as at 40, whereby the operator may readily engage the same with the finger, when the plate 38 is swung down against the plate 24.

In order to provide a means of retaining the filed cards in compact and upright position, a compression or clamping plate has been provided in the forward end of the tray. This plate is designated by the numeral 41, and is identical with that disclosed in my copending application, hereinbefore noted. The plate 41 is hingedly supported as at 42, to a suitable rigid support, designated as a whole by the numeral 43. The numeral 44 designates the operating lever for controlling the position of the plate 41.

90 The operation of the device is as follows:

Assuming that the tray contains filed matter such as cards, and that the parts are in the position illustrated in Fig. 1: It is now desired to inspect the cards, and to make this possible, the lever 44 is swung 95 over to the left, thereby releasing the clamping plate 41. The plate 38 is then moved down to permit the plate 24 to swing rearward against the brackets 27. It is now possible to inspect the cards, as all 100 pressure has been relieved therefrom. If it is desired to insert additional cards, the operator places the thumb in the seat 37, and with the finger or fingers, presses the arm 34 toward the plate 24. This action, due 105 to the rigid connection of the arm 34 with the block 31, results in raising the block 31 upward slightly against the tension of the spring 32, thus straightening said block into alignment with the carriage 28, and 110 when the parts are in this position, said carriage and associated elements may be readily moved along the track 21. Removal of the hand of the operator from the plate 24 and arm 34, will immediately result in 115 the locking of the carriage against movement.

120 It is desirable at times to insert slips or otherwise mark certain cards for further reference and to avoid the difficulty of again locating such card or cards. To obviate this difficulty, the operator releases the door 16, permitting the same to drop downward to the open position.

125 It will be observed from the foregoing that an extremely simple and efficient form of filing tray has been provided. The parts are few and so arranged as to make them easily accessible to the operator. The provision of the door is an unusually advanta- 130

geous feature, which avoids much undue time and labor in the filing of those cards which require constant inspection.

It will be observed from the foregoing that 5 an extremely simple and efficient form of follower has been provided. The parts are automatically locked upon release of the hand of the operator, while a slight pressure together of the plate 24 and arm 34 is sufficient to move the parts to the unlocked position. The parts are of such nature as to avoid the probability of becoming disarranged from normal use. The insertion of 10 the filler strips 30 avoids friction of the follower bar 25 upon the working surface of the tray, and permits an unusually easy sliding movement of the follower and carriage.

It is to be understood that the invention is not limited to the precise construction set 20 forth but that it includes within its purview whatever changes fairly come within either the terms or the spirit of the appended claims.

Having described my invention, what I 25 claim is:

1. A filing tray of the character described, comprising a rectangular body portion, open at its top, a trackway rigidly supported within said tray and upon the bottom thereof, a follower plate, a carriage for said follower plate adapted to slide in said trackway, means for hinging said follower plate to said carriage for vertical swinging movement, a projecting arm on the carriage, a 30 positioning plate hinged to the follower plate to engage the arm on the carriage and thereby force the follower plate to a vertical position, means to limit the forward swinging movement of said follower plate to the 35 vertical position, and means to limit the rearward swinging movement of said follower plate. 40

2. A filing tray of the character described, comprising a rectangular sheet-metal body portion, formed open at its top, a trackway rigidly mounted within said tray and upon the bottom thereof, a follower plate, a carriage for said follower plate adapted to engage said trackway, hinge means for connecting said follower plate with said carriage, means to limit the forward movement of said plate, means to limit the rearward swinging movement of said plate, means for rigidly supporting said plate in the forward 50 adjusted position, and clamping means for holding said carriage in adjusted position upon said trackway.

3. A filing tray of the character described, comprising a rectangular body portion, open at its top, a trackway rigidly supported therein and upon the bottom thereof, a follower plate, a carriage for said follower plate, operable upon said trackway, hinge means for connecting said plate and said carriage for vertical swinging movement of 60

the former, an arm on said carriage, a positioning plate hinged to the follower plate to engage the arm on the carriage and thereby force the follower plate to a vertical position, means to limit the rearward movement 70 of said plate, clamping means connected with said carriage and adapted to engage said trackway, and means connected with said clamping means for releasing it when the said means is pressed toward said plate. 75

4. A filing tray of the character described, comprising a rectangular body portion, formed open at its top, a trackway rigidly supported therein and upon the bottom thereof, a follower plate, a carriage for said follower plate, operable upon said trackway, means for hinging said plate and said carriage, said carriage comprising a supporting bar, brackets carried by said supporting bar for limiting the rearward swinging movement of said plate, said plate, when in its forward position, adapted to have its lower edge engage the forward edge of the supporting bar, for limiting such forward movement, a clamping means engaging said trackway, spring means connecting said clamping means and said carriage, an operating arm for said clamping means, rigidly carried thereby, a plate hingedly supported upon the rear wall of said follower plate, said latter 90 plate adapted, when swung upwardly, to engage said operating arm of the clamping means for retaining the follower plate in forward adjusted position, said operating arm for the clamping means, when moved toward the follower plate after the latter has 95 been moved to the release position, adapted to cause said clamping means to be released for permitting adjustment of the carriage upon the trackway. 100

5. A follower device of the character described, comprising a follower plate, a carriage therefor, a trackway having inturned flanges, said carriage adapted to operate upon said trackway, said carriage comprising a supporting bar, hinge means connecting said plate with said supporting bar, means for limiting the forward swinging movement of said plate, brackets carried by the supporting bar for limiting the rearward swinging movement of said plate, said carriage further comprising a horizontally U-shaped member, the parallel portions of which are adapted to engage beneath the flanges of the trackway, spacing elements 110 carried by said supporting bar and in alignment with said parallel portions, for operating above the flanges of said trackway, means to selectively clamp and release said carriage upon said trackway, comprising another 115 member slidably engaged with the latter, spring means connecting said carriage and said other member, an operating arm rigidly connected with said clamping means for releasing the same, and a plate hingedly sup- 120 125 130

ported upon said follower plate for engaging said operating arm, for supporting said plate in the forward adjusted position, while at the same time forcing said clamping means into engagement with the trackway.

6. A follower device of the character described comprising a follower plate, a carriage for said follower plate, a U-shaped trackway having inturned upper flanges, 10 said carriage adapted to engage said trackway, said carriage comprising a supporting bar, a horizontally U-shaped member rigidly attached to said supporting bar and offset therefrom for engagement beneath 15 the flanges of the trackway, hinge means for attaching said plate to said supporting bar, brackets carried by said supporting bar for limiting the rearward swinging movement of said plate, a clamping bar positioned adjacent said carriage and adapted to engage over the flanges of the trackway, a leaf spring rigidly secured to said carriage and said clamping bar, normally tending to move said clamping bar downwardly for engagement 20 with said flanges, an operating arm rigidly connected with said clamping bar, means carried by said follower plate for forcing said plate into positive operative position, said means comprising a hinged plate, sup- 25 ported upon the rear face of said follower plate, said last-named hinge plate, when in one position, adapted to engage the operating arm of the clamping means, whereby said follower plate will be forced into operative 30 position, means carried by said operating arm for limiting the upward swinging movement of said plate and spacing blocks rigidly carried by the underside of said supporting bar, adjacent said flanges, 35 and adapted to slide thereon.

7. A filing tray of the character described, comprising a rectangular body portion, formed open at its top, a trackway rigidly supported upon the bottom thereof, said trackway formed of U-shaped section and having inturned flanges, filler elements adapted to the spaces upon the opposite sides of the trackway upon the bottom of said tray, whereby the working surface of 45 the tray will be elevated to the top of the trackway, a follower plate, a carriage for said follower plate, said carriage comprising a supporting bar, a horizontally substantially U-shaped runner member, rigidly supported upon said bar and offset for engaging below the flanges of the trackway, means to selectively clamp and release said U-shaped member, spacing blocks rigidly supported upon the under face of said supporting bar, and in alignment with said flanges, whereby said supporting bar will be ele- 50 55 60 65 70 75 80 85 90 95 100 105 110 115 120

vated slightly above the working surface of the tray, said spacing blocks adapted to slide upon the upper surface of said flanges, a clamping member positioned adjacent said carriage, a flat leaf spring, rigidly connected with said carriage and with said clamping member, and normally tending to move said clamping member downwardly for engagement with said flanges, said clamping member comprising a bar grooved at its ends for engagement over said flanges, an operating arm rigidly connected with said clamping bar and offset slightly rearwardly from the vertical, hinge means connecting said follower plate with said supporting bar, means for limiting the forward swinging movement of said follower plate, rigid brackets carried by said supporting bar for limiting the rearward swinging movement of said plate, means carried by said plate adapted to engage said operating arm for forcing said plate into positive operative position, means to limit the movement of said last-named means, said operating arm acting to release said clamping means when moved toward the follower plate.

8. A follower device of the character described, comprising a follower plate, a carriage therefor, a U-shaped trackway having inturned flanges, adapted to receive said carriage, a clamping member arranged adjacent said carriage, said clamping member comprising a bar having grooved ends adapted to engage over the flanges of said trackway, spring means connecting said carriage and said clamping member whereby said clamping member is adapted to be normally moved downwardly for frictional engagement with said flanges, an operating arm rigidly connected with said clamping member, means for hingedly supporting said follower plate upon said carriage, said carriage comprising a horizontally U-shaped runner member rigidly attached to a supporting bar and offset for engagement beneath the flanges of the trackway, spacing blocks rigidly supported upon the bottom surface of a supporting bar for sliding engagement with the upper surface of the flanges, means to limit the forward swinging movement of the follower plate, means to limit the rearward swinging movement of the follower plate, said operating arm, when moved toward said follower plate against the tension of the spring means acting to move the clamping member into alignment with the carriage for permitting the free movement of the carriage and clamping means longitudinally of said flanges, all as substantially shown and described.

NELSON S. WELK.
